UNITED STATES PATENT OFFICE.

LOESER KALINA, OF NEW YORK, N. Y.

GARMENT-HANGER.

1,114,002.

Specification of Letters Patent. Patented Oct. 20, 1914.

Application filed March 8, 1913. Serial No. 752,975.

To all whom it may concern:

Be it known that I, LOESER KALINA, a citizen of the United States, and a resident of the city of New York, borough of Brooklyn, in the county of Kings and State of New York, have invented a new and Improved Garment-Hanger, of which the following is a full, clear, and exact description.

The object of the invention is to provide a new and improved garment hanger, which is simple and durable in construction and arranged to permit the user to fold it into a comparatively small space for convenient carrying in a vest pocket, suit case, traveling bag or the like, and to allow of readily extending it and hanging it up on a suitable support for supporting coats, vests, suits, trousers, skirts, shirt waists and other garments.

In order to accomplish the desired result use is made of side arms in foldable sections, a casing open at the sides and adapted to hold the said side arms in extended or folded position, and a cover held to slide on the said casing and adapted to open and close the open sides thereof.

A practical embodiment of the invention is represented in the accompanying drawings forming a part of this specification, in which similar characters of reference indicate corresponding parts in all the views.

Figure 1 is a side elevation of the garment hanger and showing the cover open and the side arms in extended position; Fig. 2 is an enlarged sectional side elevation of the same with the cover closed and the side arms folded within the casing; Fig. 3 is an edge view of the same; Fig. 4 is a sectional side elevation of the upper portion of the casing and the lower portion of the cover in raised position; Fig. 5 is a sectional plan view of the garment hanger on the line 5—5 of Fig. 2; Fig. 6 is a similar view of the same on the line 6—6 of Fig. 2; Fig. 7 is a sectional plan view of one side of the cover; Fig. 8 is a reduced plan view of the blank for forming the cover; and Fig. 9 is a similar view of the blank for forming the casing.

In the general construction of the garment hanger use is made of a casing A and sectional side arms B, B', each preferably made of telescoping sections B², B³, B⁴ and B⁵, the side arms being adapted to be folded within the casing, as shown in Fig. 2, or

extended from the sides thereof, as shown in Fig. 1, for supporting the garment or garments. The casing A is open at the sides for moving the side arms into folded or extended position, and the casing is preferably formed from a single blank of sheet metal or other material (see Fig. 9) bent to provide a bottom A', a front A² and a back A³, the upper ends of the front and back terminating in transverse top pieces A⁴, A⁵ extending toward each other and having upwardly-extending lugs A⁶, A⁷ forming a central pivot and passing through a central opening in a top plate C overlying the top pieces A⁴, A⁵. The terminals of the lugs A⁶, A⁷ are bent transversely in opposite directions (see Fig. 5) onto the upper surface of the top plate C so as to hold the latter in place but to allow the top plate to turn on the pivot formed by the lugs A⁶, A⁷.

A cover D is used for closing the open sides of the casing A at the time the side arms B, B' are in folded position within the casing A, as indicated in Fig. 2, and the cover D is formed from a single blank of sheet metal or other material (see Fig. 8) bent to provide a top D' and side plates D², D³ engaging vertically-disposed grooves A⁸, A⁹ formed in the inner faces of the front A² and the back A³ of the casing A. The side plates D², D³ extend through slots C², C³ formed in the top plate C so that when the cover D is raised to its full extent as shown in Figs. 1 and 4 then it can be turned with the top plate C. The lower ends of the side plates D² and D³ of the cover D are provided with lugs D⁴, D⁵ adapted to engage openings A¹⁰ formed in flanges A¹¹ extending upwardly from the sides of the bottom A' of the casing A. The lower ends of the side plates D², D³ are also provided with inwardly extending lugs D⁷ adapted to fit the exterior faces of the sections B² of the side arms B, B' when moving the cover D upward into open position or downward into closed position. The lugs D⁴, D⁵, D⁶ and D⁷ are adapted to abut against the under side of the top plate C to limit the upward movement of the cover D when the latter is raised.

The upper portions of the front A² and the back A³ are cut out as indicated at A¹² to provide sufficient room for the lugs D⁴, D⁵, D⁶ and D⁷ at the time the cover D is raised, the cut-out portions A¹² permitting

free turning of the cover D and with it the top plate C.

It is understood that when the cover D is pushed downward the lugs D⁴, D⁵ snap into the openings A¹⁰ to lock the cover in place when in closed position. When it is desired to raise the cover D it is only necessary for the operator to exert a slight inward pressure on the side plates D², D³ to disengage the lugs D⁴, D⁵ from the openings A¹⁰ to allow lifting of the cover D into open position.

The innermost sections B² of the side arms B and B' are connected by pivots E with the front A² and the back A³ of the casing to permit of conveniently swinging the side arms into open or closed position. When the side arms B, B' are swung into open position as indicated in Fig. 1, then the inner sections B² of the side arms B, B' rest on the top edges of the flanges A¹¹ to support the side arms in a slightly inclined position, as indicated in Fig. 1.

A double spring F is held between the lugs A⁶, A⁷, and the free ends of the members of the double spring F extend into the casing A between the innermost sections B² and the side arms B, B', and the free ends of the members of the double spring F are compressed when swinging the folded side arms B and B' into the casing (see Fig. 2), so that when the cover D is raised into open position the spring F imparts an outward swinging motion to the sections B² so as to cause the same to swing downward into open position.

The sections B³, B⁴ and B⁵ freely telescope and at the time the side arms swing into open position after being released by the cover D the sections B³, B⁴ and B⁵ slide outward of their own accord into extended position.

It is understood that when the cover D is moved upward the lugs D⁶, D⁷ press the sections B² of the side arms B and B' slightly inward so that the spring F is placed under more tension, and when the lugs D⁶, D⁷ have left the upper ends of the sections B² then the spring F forces the sections apart so that the same swing downward into open position as previously mentioned.

By giving the cover D an approximately inverted U-shaped form the cover can be readily hooked onto a nail or other support for suspending the garment hanger from such support, and as the cover D and the top plate C have a swivel connection with the casing A the latter can be turned around so as to permit of conveniently placing a garment in position on the extended side arms B, B' or removing such garment therefrom.

The garment hanger constructed in the manner described takes up comparatively small space when the parts are folded, and

the garment hanger can be cheaply manufactured and readily folded or extended as desired.

Having thus described my invention, I claim as new and desire to secure by Letters Patent:

1. A garment hanger, comprising side arms made in foldable sections, a casing open at the sides and adapted to hold the said side arms in extended or folded position, and a cover mounted to slide up and down on the said casing to open and close the open sides thereof. 75

2. A garment hanger, comprising side arms made in foldable sections, a casing open at the sides and adapted to hold the said side arms in extended or folded position, a cover slideable on the said casing to open and close the open sides thereof, and a top plate mounted to turn on the top of the said casing and slidably engaged by the said cover to allow of turning the top plate and cover at the time the latter is in open position. 80

3. A garment hanger, comprising side arms made in foldable sections, a casing open at the sides and adapted to hold the said arms in extended or folded position, the casing being provided with vertical guideways adjacent the open side arms, a cover having side arms slideable in the said guideways, and a top plate held on the said casing and limiting the cover in its outward sliding movement. 95

4. A garment hanger, comprising side arms made in foldable sections, a casing open at the sides and adapted to hold the said side arms in extended or folded position, the casing being provided with vertical guideways adjacent the open side arms, a cover having side arms slideable in the said guideways, and a top plate held on the said casing and limiting the cover in its outward sliding movement, the said top plate being mounted to turn on the casing and slidably engaged by the said cover. 100

5. A garment hanger, comprising side arms made in foldable sections, a casing open at the sides and adapted to hold the said side arms in extended or folded position, a cover slideable on the said casing to open and close the open sides thereof, and a spring device held in the middle of the top portion of the casing and adapted to be engaged by the said side arms to start the same on sliding the cover into an open position. 115

6. A garment hanger, comprising side arms made in foldable sections, a casing open at the sides and adapted to hold the said side arms in extended or folded position, and a cover slideable up and down on the said casing to open and close the open sides thereof, the said cover and casing having interlocking means for locking the cover in closed position. 125

7. A garment hanger, comprising side arms made in foldable sections, a casing open at the sides and adapted to hold the said side arms in extended or folded position, the casing being provided with vertical guideways adjacent the open side arms, and a cover having side arms slideable in the said guideways, the said side arms having lugs and the casing having apertured flanges rising from the bottom, the flanges being adapted to be engaged by the said lugs to lock the cover in closed position.
8. A garment hanger, comprising side arms made in foldable sections, a casing open at the sides and adapted to hold the said side arms in extended or folded position, the casing being provided with vertical guideways adjacent the open side arms, a cover having side arms slideable in the said guideways, the said side arms having lugs and the casing having apertured flanges rising from the bottom, the flanges being adapted to be engaged by the said lugs to lock the cover in closed position, and a top plate mounted to turn on the top of the said
- casing and slidably engaged by the side arms of the cover, the casing and its guideways having cut-out portions at the upper end adjacent the open sides to allow of turning the top plate and the cover at the time 30 the latter is in open position.
9. A garment hanger, comprising side arms made in foldable sections, a casing open at the sides and in which the said side arms are pivoted to hold the said side arms 35 in extended or folded position and a cover mounted to slide up and down on the said casing to open and close the open sides thereof, and means pivotally connecting the cover with the top of the casing to allow turning 40 of the cover at the time the cover is in uppermost open position.

In testimony whereof I have signed my name to this specification in the presence of two subscribing witnesses.

LOESER KALINA.
